TOY ANIMAL FIGURE OR THE LIKE

Rose Mirman, Paris, France

Application April 14, 1948, Serial No. 145,725
In France January 12, 1948

Term of patent 7 years

(Cl. D34—2)

To all whom it may concern:

Be it known that I, Rose Mirman, a citizen of France, residing at Paris, France, have invented a new, original, and ornamental Design for Toy Animal Figure or the like, of which the following is a specification, reference being had to the accompanying drawing, forming part thereof.

Fig. 1 is a partly rear and partly side view of a toy animal figure, showing my new design;

Fig. 2 is a front view of the toy animal figure in Fig. 1; and

Fig. 3 is a side view of the toy animal figure shown in Figs. 1 and 2.

I claim:

The ornamental design for a toy animal figure or the like, as shown and described.

ROSE MIRMAN.
